UNITED STATES PATENT OFFICE

2,562,671

CLOTHES HANGER FOR IRONING BOARDS

Leonard W. Kois, Chicago, Ill.

Application December 27, 1949, Serial No. 135,087

1 Claim. (Cl. 211—86)

1

My invention relates to devices designed for application to ironing boards for the support of garments in a handy place after they have been ironed, and one object of the present invention is to provide a device of this kind which may be easily attached to one end of the ironing board to extend rearwardly thereof in an out-of-the-way position.

A further object is to design the device with one portion as a spring clamp for the ironing board and a continuation of such portion in the form of a bracket formed with hooks for the suspension of hangers on which the garments are hung.

Another object is to construct the novel device with a bottom portion to serve as the clamp referred to, and to extend the continuation in a poised position, so that the garments may be suspended at a height where they will not touch the floor or hang close to the same.

An additional object is to construct the device in one piece from sturdy material, whereby to make its manufacture inexpensive and render the device durable over a long period of use.

With the above objects in view, and any others which may suggest themselves from the description to follow, a better understanding of the invention may be had by reference to the accompanying drawing, in which—

Fig. 1 is a perspective view of the device, showing its application;

Fig. 2 is an enlarged top plan of the device with a fragment of the ironing board shown;

Fig. 3 is a side elevation of the device on the same scale as in Fig. 2;

Fig. 4 is a top plan view of a fragment of the device on a magnified scale; and

Fig. 5 is a section on the line 5—5 of Fig. 4.

Referring specifically to the drawing, 10 denotes a typical ironing board of the table type, and it is noted in Fig. 1 that the novel device is applied to the rear end of the board.

The device is primarily in the form of a broad steel clamp 12, which is slid over the rear end of the board 10 to assume the position shown in Fig. 3, the clamp being designed to exert a firm grip on the table.

The clamp 12 takes an upward curve at 13 and a return bend 14, the latter being of reduced width. The bend 14 continues as a bracket 15 which rises inclinedly to a poised position behind the board, terminating with a slight downward curve as indicated at 16. While the material of the clamp 12 is flat stock, the bend 14

2

and bracket 15 are formed as a channel having upward walls 17. Finally, a number of hooks 18 are struck down from the floor of the bracket to extend rearwardly as shown in Fig. 3, the hooks being spaced equally along the bracket.

When the use of the device is required it may be quickly clamped to the ironing board as shown in Fig. 3. Then, after each garment has been ironed it may be hung on a conventional hanger 19 and suspended from one of the bracket hooks 18 as shown in Fig. 1. Thus, the garments are disposed of conveniently and without necessitating the person ironing to leave the region of the ironing board; and the garments are hung away from

surrounding furniture, walls, or other objects so that they will not become soiled or creased. Further, the rise of the bracket 15 makes it convenient to hang the shorter garments on the lower hooks and the longer ones on the higher hooks,

so that all the garments will hang high above the floor and be safe against soiling from bottom contact. Further, the bracket 15 is sufficiently long to accommodate a relatively large number of garments. It is understood that garments

commonly ironed at home are of light weight, and they will therefore not impose any strain on the bracket 15 or assume a tendency to overbalance the ironing board. Further, the form of the device and the position of its application

to the board make it a continuation of the latter, so to speak, leaving the space on both sides of the board and the device clear for passage, so that the device may be considered as both convenient to the person doing the ironing and out

of the way insofar as the surrounding space is concerned. Finally, it is apparent that the device, by its one piece construction, is of utmost simplicity; and it may be made of sufficient strength to be durable over a long period of use.

While I have described the invention along specific lines various minor changes or refinements may be made therein without departing from its principle, and I reserve the right to employ all such changes and refinements as may come within the scope and spirit of the appended claim.

I claim:

A clothes hanger for a table type ironing board comprising a substantially U-shaped spring clamp engageable with the ironing board from the side, the upper portion of the clamp being continued in upward direction with a return bend, an extension of the latter with a rising incline, the sides of said upper portion converging with up-

ward walls to form said return bend and extension into a channel shaped bracket, and a longitudinal series of hooks struck down from the bottom of said bracket to serve as garment hanger supports.
